DESIGN FOR A FINGERNAIL PROTECTOR

John A. Belmonte and Alexander E. Shagen,
Brooklyn, N. Y.

Application November 2, 1942, Serial No. 108,680

Term of patent 3½ years

To all whom it may concern:

Be it known that we, John A. Belmonte and Alexander E. Shagen, both citizens of the United States and both residing at Brooklyn, in the county of Kings and State of New York, have invented a new, original, and ornamental Design for a Fingernail Protector, of which the following is a specification, reference being had to the accompanying drawing, forming part thereof.

Fig. 1 is a side view of a fingernail protector, showing our new design.

Fig. 2 is a top plan view thereof.

Fig. 3 is a bottom plan view thereof.

Fig. 4 is an end view thereof.

We claim:

The ornamental design for a fingernail protector, substantially as shown.

JOHN A. BELMONTE.
ALEXANDER E. SHAGEN.
